UNITED STATES PATENT OFFICE.

JOSEPH W. WEISS, OF BALTIMORE, MARYLAND.

COLLAPSIBLE OR KNOCKDOWN BOX.

1,063,845.

Specification of Letters Patent.

Patented June 3, 1913.

Application filed October 16, 1912. Serial No. 726,003.

To all whom it may concern:

Be it known that I, JOSEPH W. WEISS, a citizen of the United States, and a resident of Baltimore, in the State of Maryland, have 5 invented certain new and useful Improvements in Collapsible or Knockdown Boxes, of which the following is a specification.

This invention relates to collapsible or knock-down boxes, more particularly to the 10 type known as the slotted carton.

The principal object of the present invention is to provide a form of box or carton of this description which shall be of stiff and rigid construction so as to be able to 15 withstand rough usage in handling and knocking about which these boxes undergo when shipped from point to point with articles of merchandise packed therein.

Further objects and advantages will appear from the detailed description and particularly pointed out in the claims.

Collapsible or knock-down boxes have come into vogue by reason of their advantageous characteristic in taking up little 25 room when in collapsed or knock-down condition, so that a great many may be kept on hand, stored and used from time to time as occasion requires. Hitherto, however, boxes of this description have been limited in their 30 capacity as to the weight of the articles to be packed therein by reason of their flimsy construction and their inability to stand rough handling during the course of shipment or transportation. Railroad companies 35 have been accustomed to place a limit on the permissible weight of material which may be transported in each box owing to the flimsiness in construction which endangers the bursting of a box or its mutilation. 40 When roughly handled while containing more than a certain weight of material.

When devising means for strengthening these boxes, it is necessary to bear in mind that boxes of this description must be light 45 and cheap; otherwise their cost and added expense in transportation would materially detract from the other advantages. I have, therefore, provided a collapsible box or slotted carton in which the material of the 50 box itself is so disposed and formed that a maximum of strength and rigidity is obtained.

In making the box, I form the blank with two or more folds which increase the 55 strength of material and the stiffness and rigidity just at the points which receive most

of the impact incident to the knocking about and rough handling of the box. In one of the forms of my invention these folds are disposed at the end edges of the box adjacent to the flaps. This results in the ends of the box being not only strengthened but also formed with lateral projections which protect the body of the box from impact. These projections receive any blow which the box may receive in dropping or in being struck by an external object and also space the body from the supporting surface, so that the weight of another body resting on the same is borne by these end projections 70 which are also reinforced by the flaps constituting the lid of the box. In some cases, I prefer to insert metallic corner pieces within the folds at the corners which as a rule bear the brunt of the knocks. These 75 metallic pieces may be kept separate when the boxes are collapsed and readily inserted when they are set up. In other cases, I prefer to embed a wire, metal strip or non-metallic string or tape within the folds to 80 further strengthen the ends of the box and to facilitate the sealing of the same. In other forms of my invention additional transverse folds may be formed in the body of the box or longitudinal folds may be 85 formed on the longitudinal edges or intermediate portions of the body of the box.

In the accompanying drawings, Figure 1 is a perspective view illustrating one form of my invention with the folds situated at 90 the end edges of the box. Fig. 2 illustrates the carton partly collapsed. Fig. 3 is a fragmental side view illustrating the folds as extending further down the body of the box so as to reinforce it for a greater length. 95 Fig. 4 is a fragmental section and Fig. 5 is a perspective view of a form in which the flaps are made separate from the body and are formed in one piece at each end, making a three part construction for the entire carton. Fig. 6 is a fragmental section of another form of three part construction, the fold being made in the flap instead of the body. Fig. 7 is a fragmental section illustrating another form in which the fold is 100 partly in the body and partly in the flap. Fig. 8 is a section illustrating a metal reinforcement used at the corners. Fig. 9 is a perspective view illustrating the angle piece used for this reinforcement. Fig. 10 illustrates a form in which a wire or tape is 105 threaded through the fold to reinforce the 110

ends of the box. Fig. 11 is a perspective view illustrating a preferred form of metal reinforcement to be used at the corners. Fig. 12 is a perspective view illustrating a modified form having transverse folds in the body of the box. Figs. 13 and 14 are perspective views illustrating modifications with longitudinal folds at the edges and intermediate portions of the sides of the box.

Referring to Figs. 1 and 2, the carton is formed of a blank which is scored longitudinally so as to readily form its longitudinal sides 1, 2, etc., and also scored on lines adjacent to its ends. The ends are then slitted so as to form flaps 3, 4, 5 and 6, each containing sections 7 and 8 formed by the scoring. The latter are then folded over into an S shaped fold and attached to the sides 1, 2 etc. in any desired manner as by staples 9. The meeting edges of sides 1 and 2 are then united by a strip 10 of canvas or other suitable flexible material which is pasted, glued or otherwise attached thereto. The box is then complete and ready for shipment in knock-down condition. When it is desired to set it up, the edges 11 and 12 on the sides 1 and 2 are compressed inwardly so as to give the box its rectangular shape whereupon the flaps 3 and 4 are turned over and flaps 5 and 6 are also turned over so as to lie on top of the flaps 3 and 4. The contiguous faces of the flaps may be gummed or have other attaching means thereon to firmly secure them to each other and close the ends of the box. When one end is thus closed, the articles to be packed are inserted in the box, the other end of the box is similarly closed and it is then ready for shipment. In some cases when it is desirable to still further strengthen the box, I may insert preferably metallic corner strengthening pieces such as illustrated in Fig. 11, the same consisting of a bracket-like construction having angularly disposed sides 13 and 14 and a uniting top portion 15. (See Fig. 11.) I have indicated these angle pieces in dotted lines in Fig. 1.

In Fig. 3, a construction is shown wherein the sections 7^a and 8^a, corresponding to sections 7 and 8 in Figs. 1 and 2, are extended downward further so as to strengthen the body of the box in addition to the ends, otherwise the construction is the same as in Figs. 1 and 2.

In Figs. 4 and 5, I have illustrated a three piece construction, the body of the box having the sides 1^b and 2^b, etc. separate from the top and bottom pieces containing flaps 3^b, 4^b, 5^b and 6^b. The section 7^b is integral with the body of the box while the section 8^b is integral with the flap portion. This section 8^b extends all the way around the box and conceals the raw meeting edges of the section 7^b, thus adding to the appearance of the box and further strengthening the same.

In the construction illustrated in Fig. 6, the end pieces contain the folded sections while the body of the box is not folded. The fold consists of sections 7^c and 8^c extending around the box and having the flaps 3^c, 4^c, etc. integral therewith.

In Fig. 7, I have illustrated a form in which the inner section of the fold is formed of two parts, one of which 7^d is formed integral with the body of the box, while the other portion 7^e and also the outer section of the fold 8^d are formed integral with the flaps 3^d, 4^d, etc. The portions of the fold 7^d and 7^e abut each other and are secured to the body of the box in any desired way together with the section 8^d.

In a simplified form of strengthening the corners, I insert preferably metallic angle pieces 16 (see Fig. 9) within the folds of the flaps. These angle pieces may be formed of metal or other stiff material and assembled in place when the boxes are set up. (See Fig. 8.)

In Fig. 10, I have illustrated a wire or tape 17 inserted at the bottom of the fold and extending all around the box so as to further strengthen the ends. This wire or tape may be inserted within the folds before they are attached together and may be permanently held therein, and if desired, the ends of the wire or tape may be fastened with a seal 17^a to prevent unauthorized tampering with the contents of the box. This is especially efficacious in boxes having the intermediate fold such as illustrated in Fig. 12 hereinafter described.

In Fig. 12, I have illustrated a form in which transverse folds 18 are formed also in the body of the box intermediate the ends so as to further strengthen the box at intermediate points. If desired, these folds may be multiplied to any required number according to the purpose for which the box is designed.

In Fig. 13 a form of construction is illustrated wherein the folds 19 are formed at the longitudinal edges instead of at the end edges of the box. In this form of construction the fold is preferably formed on each side of a longitudinal edge forming a double S as clearly shown in this figure. The material may, if desired, be cut away during the formation of the blank or at any time thereafter so as to leave the flaps free from the fold.

In Fig. 14 a form is illustrated with longitudinal double S shaped folds 20 located at or near the middle of the longitudinal sides. The outer flaps 5^a and 6^a are preferably shortened so as to abut the fold or ridge extending on the inner flaps 3^a and 4^a, the fold on the flaps thus forming a cross or strengthening spider materially increasing the strength of the ends of the box.

It will thus be seen that I have provided a

collapsible box or carton which is strong and durable and is capable of withstanding considerable rough handling. However, the cost of manufacturing these boxes is not appreciably increased as the result is produced principally by the proper disposition of the material from which the box itself is built up. The angle pieces which may be used for the corners may be very cheaply made and can very readily be slipped in when the box is set up without requiring any apparatus or tools. A wire or tape, or other strengthening strip may very readily be embedded or attached within the folds at a slight additional expense in cost of material and manufacture and thus further strengthening the box.

It will be noted that in all of the forms I have disclosed, the box rests on its reinforced edges causing the latter to receive the bulk of the weight and impact and thus protecting the comparatively weak body portion of the box.

Various modifications may be made within the skill of a mechanic without departing from the spirit and scope of the invention as defined in the claims.

Having thus described my invention, I claim—

1. A collapsible box of fibrous material having sides, an end flap for each side, and reinforcing folds at the edges of the box between the flaps and sides, said folds and flaps formed integral with the sides of the box and forming projecting strengthening ridges at the edges so as to space the sides from the supporting surface upon which the box may rest and means for attaching said folds to said sides.

2. A collapsible box having sides and end flaps, folds formed integral with said sides and flaps, said folds forming a projecting ridge about the ends of the box, and stiff angle pieces located within said folds at the corners, said angle pieces being partially concealed by the flaps.

3. A collapsible box having sides, an end flap extending from each side, folds formed between said flaps and sides, said folds and flaps being integral with the sides, and a reinforcing member extending within said folds and concealed by the flaps.

4. A collapsible box having sides, an end flap extending from each side, and a fold between said flaps and sides at the exterior of the box at the end thereof, said fold forming a reinforcing ridge extending around the box and spacing the same from the surface on which the box is supported and means for permanently fastening said folds to the sides.

5. A collapsible box having sides and end flaps, folds formed integral with said sides and flaps, said folds forming a projecting ridge about the ends of the box, stiff angle

pieces located within said folds at the corners, said angle pieces comprising angularly disposed arms and a stiffening portion embracing said arms located on one side thereof.

6. A collapsible carton comprising side portions adjustable to form a rectangular box, flaps extending from said side portions and formed integral therewith, a fold formed adjacent to the junction of the flaps and sides, said fold being of S shape and attached to the sides, and angular corner pieces within said folds and substantially concealed by the flaps.

7. A collapsible carton comprising side portions adjustable to form a rectangular box, flaps extending from said side portions and formed integral therewith, a fold formed adjacent to the junction of the flaps and sides, said fold being of S shape and attached to the sides, and angular corner pieces within the folds, said angular pieces having a bracing portion extending over the edges of the sides and supporting the flaps thereon.

8. A collapsible box formed entirely of fibrous material, said box having rectangular sides, and S shaped folds formed on each side of the box out of the material thereof so as to form strengthening ridges for reinforcing the box and adapted to bear the weight of the box and to space the body thereof from the supporting surface and means for permanently attaching the folds to the body.

9. A collapsible box formed entirely of fibrous material, said box having rectangular sides, transverse folds formed on the exterior of each side of the box out of the material thereof so as to form stiffening ridges for reinforcing the box, one set of said folds being disposed at the end of the box and another set of said folds being formed intermediate the ends, all of said folds being adapted to bear the weight of the box and space the body thereof from the supporting surface.

10. A collapsible box formed entirely of fibrous material, said box having rectangular sides, transverse folds formed on the exterior of each side of the box out of the material thereof so as to form stiffening ridges for reinforcing the box, one set of said folds being disposed at the end of the box and another set of said folds being formed intermediate the ends, all of said folds being adapted to bear the weight of the box and space the body thereof from the supporting surface, and a sealing member extending through said intermediate fold.

11. A collapsible box formed of fibrous material and provided at each end with a reinforcing fold which extends around the ends of the box, projects outward from the sides, and is permanently attached thereto;

and flaps extending from said folds to form closures for the ends of the box.

12. A collapsible box formed of an integral sheet of stiff fibrous material having 5 longitudinal scores to form flexible corners for the sides; an S shaped fold extending entirely around each end of the box, projecting outward from the sides, and permanently attached thereto; and flaps extending 10 from said folds to form closures for the ends of the box.

13. A collapsible box formed of an integral sheet of stiff fibrous material having longitudinal scores to form flexible corners

for the sides, said sides being slit at the 15 ends and doubled back on themselves to form S shaped folds projecting outward from the sides and permanently attached thereto; and integral flaps extending from said folds to form closures for the ends of 20 the box.

Signed at New York city, in the county of New York, and State of New York, this 11th day of October A. D. 1912.

JOSEPH W. WEISS.
